(57) **CLAIM**

The ornamental design for a mobile device stand, as shown and described.

DESCRIPTION

FIG. 1 is an upper perspective view of one embodiment of a mobile device stand showing my new design;

FIG. 2 is an upper perspective view thereof taken from a different orientation;

FIG. 3 is a lower perspective view thereof;

FIG. 4 is a lower perspective view thereof taken from a different orientation;

FIG. 5 is a top plan view thereof;

FIG. 6 is a front elevational view thereof, the rear, left and right side elevational views being identical;

FIG. 7 is a bottom plan view thereof;

FIG. 8 is a side elevational view thereof shown in a use condition;

FIG. 9 is a side elevational view thereof shown in an alternate position;

FIG. 10 is a lower perspective view thereof;

FIG. 11 is an upper perspective view thereof;

FIG. 12 is a side elevational view thereof shown in a use condition;

FIG. 13 is a side elevational view thereof shown in an alternate position and a use condition; and,

FIG. 14 is a side elevational view thereof shown in an alternate position and a use condition.

The broken lines are for illustrative purposes only and form no part of the claimed design.
